SWITCH

Arnold J. Burger, New York County, N. Y.

Application October 29, 1949, Serial No. 5,785

Term of patent 7 years

(Cl. D26—13)

To all whom it may concern:

Be it known that I, Arnold J. Burger, a citizen of the United States, residing at 50 West 9th Street, in the county of New York and State of New York, have invented a new, original, and ornamental Design for Switches, of which the following is a specification, reference being had to the accompanying drawing, forming part thereof.

Fig. 1 is a perspective view of a switch, disclosing my new design. Fig. 2 is a side elevational view of the switch shown in Fig. 1. Fig. 3 is

a sectional view taken along a vertical plane through the switch shown in Figures 1 and 2.

I claim:

The ornamental design for a switch, as shown.
